UNITED STATES PATENT OFFICE.

RICHARD LAUCKNER, OF BAY CITY, MICHIGAN.

VALVE.

SPECIFICATION forming part of Letters Patent No. 288,350, dated November 13, 1883.

Application filed January 31, 1883. (No model.)

To all whom it may concern:

Be it known that J, RICHARD LAUCKNER, of Bay City, in the county of Bay and State of Michigan, have invented new and useful Improvements in Valves; and I hereby declare that the following is a full, clear, and exact description thereof, reference being had to the accompanying drawings, which form a part of this specification.

10. This invention relates to that class of valves commonly called "rotary" valves; and the invention consists in the peculiar and novel shape of the valve face and seat, by means of which the valve is kept steam or water tight during a long period of use without the necessity of refacing it, and without the use of any packing whatever, all as more fully hereinafter described.

Figure 1 is a vertical central section of my 20 improved valve, taken through the axis of the inlet and outlet couplings. Fig. 2 is a horizontal section on line XX. Fig. 3 is a vertical central section of the valve, taken at right angles to the one in Fig. 1. Fig. 4 is a diagram 25 section of my improved valve-face and of the ordinary conical one.

In the accompanying drawings, A represents the lower and B the upper half of the valve-shell, each provided with a corresponding 30 annular ring, *a*, by means of which the two halves can be fitted together steam-tight.

C is the inlet and D the outlet coupling.

E is the valve proper. Its face is conoidal, and has been generated by the concave line 35 F, which shows the valve-face in section.

b b are two ports in the valve, diametrically opposite each other and corresponding with two ports, *c c*, in the valve-seat G. The two ports *c* lead into ducts *d*, cast in the upper 40 valve-shell, and leading both into the outlet-coupling D. In the drawings the valve-seat G is cast integral with the upper half of the shell, and is of proper shape to fit the face of the valve steam-tight.

45. H is the valve-stem, and I the valve-handle, by means of which it can be rotated.

K is a nut which secures the handle upon the stem and allows the valve to be tightened to its seat.

In practice the valve is opened by making the ports *b* and *c* coincide. It has been demonstrated in practice that in all rotary valves where the valve-face is either a plane disk or a cone the valve begins to leak after having been in use some time, and this is entirely owing to the unequal wear of the valve-face upon its seat when in operation, as the parts farther away from the center of rotation have to traverse part of a larger circle than those nearer the center. The result is that the valve-face gets more worn away nearer the edges than toward the center, and nothing but refacing can make it steam-tight.

In the diagram in Fig. 4, I show my improved valve-face and an ordinary conical one, the lower lines showing the worn faces of each. It is clear that the conical face, after it is worn, will not fit its seat steam-tight; but my valve-face, after being worn off, may be perfectly parallel to the original face, providing its concavo generating curve has been properly selected, which may easily be done by the constructor, if he proportions his curve so as to make up for the loss of travel toward the center of the valve by a corresponding comparative increase of the wearing-surface.

It is clear that the material of which the valve and valve-seat are made does not affect the question of unequal wear. In practice both the valve-seat and the valve-face will wear off; but it is clear that if one is adjusted to wear off evenly the other will do the same.

What I claim as my invention is—

In a rotary valve, the parts A and B, the former having the inlet-coupling C, and the latter having the ports *c c*, water-way *d*, connecting said ports and outlet-coupling D, combined with the conoidal valve E, having ports *b b*, arranged to register with the ports *c c* when the cock is open, and adapted to close 90 the said ports by a quarter-turn of the valve-stem H, as set forth.

RICHARD LAUCKNER.
